TIP FOR CIGARETTES

Filed Sept. 16, 1932

INVENTOR.
Helen Hill,
BY John O. Brady
ATTORNEY.

UNITED STATES PATENT OFFICE

1,959,717

TIP FOR CIGARETTES

Helen Hill, Washington, D. C., assignor of one-half to Radio Research Company, Inc., Washington, D. C., a corporation of Delaware

Application September 16, 1932, Serial No. 633,507

1 Claim. (Cl. 131—10)

My invention relates broadly to smoking appliances and more particularly to a mouthpiece or tip for cigarettes.

One of the objects of my invention is to provide a construction of tip for cigarettes which will permit the enjoyment of smoking without the adverse effects of staining the mouth or teeth or the removal of cosmetics from the lips.

Another object of my invention is to provide a construction of tip for cigarettes by which a support may be provided for the drawing end of the cigarette to enable the cigarette to be rested upon a supporting surface from time to time intermediate the smoking intervals.

15 A further object of my invention is to provide a construction of tip for cigarettes which may be employed as a holder for various brands of cigarettes for avoiding finger stain and providing means whereby the cigarette may be held between the teeth and out of moisture absorbing contact with the lips.

20 A still further object of my invention is to provide a construction of metallic tip for supporting a cigarette in which a substantially Venturi shape is imparted to the tubular member forming the cigarette tip for permitting ready insertion or removal of the cigarette from the tip.

Other and further objects of my invention reside in the construction of sanitary cigarette 30 holder adapted to reduce the effects of nicotine as set forth more fully in the specification hereinafter following by reference to the accompanying drawing, in which:

Figure 1 is a side elevational view showing a cigarette supported in the cigarette tip of my invention; Fig. 2 is a cross-sectional view through the cigarette and cigarette tip; Fig. 3 is a cross-section view taken through the cigarette tip of my invention. Fig. 4 is a cross-sectional view through the cigarette tip on line 4—4 of Fig. 3; Fig. 5 illustrates one of the uses of the cigarette tip of my invention as a vertical support for the cigarette intermediate the smoking intervals; Fig. 6 is a side elevational view of a modified form of cigarette tip showing a ring shaped holder which I may provide for supporting the cigarette from the finger; Fig. 7 is a cross-sectional view taken through the cigarette tip and support on line 7—7 of Fig. 6; 45 and Fig. 8 is a perspective view of the cigarette tip having a ring support connected therewith and mounted from the finger of the smoker.

50 My invention is directed to a construction of tip for cigarettes which may be manufactured inexpensively on a quantity production basis and

which may carry advertising matter thereon and adapted to be distributed as an advertising novelty. The cigarette tip may also be formed from metallic metal plated with gold, platinum or other metals to avoid tarnishing or any adverse effects on the mouth or teeth. The tip is substantially in the shape of a Venturi tube having its smallest diameter intermediate its ends and flaring outwardly at opposite ends. The diameter of the tip at its smallest cross-section is approximately $\frac{1}{8}$ of an inch or of a size to snugly receive the end of the cigarette. The length of the cigarette tip is relatively short, that is, approximately $\frac{5}{8}$ of an inch so the tip may be held between the teeth and the lips protected from contact with the end of the cigarette which may become moistened.

Referring to the drawing in detail, reference character 1 designates a cigarette inserted in the tubular tip 2 of my invention. The tubular tip 2 has a Venturi shape with a minimum diameter at its central portion 3 flaring outwardly to a maximum diameter at the end 4 and at the end 5. The flared end 5 permits insertion of the cigarette 1 which is snugly confined in the portion of minimum diameter 3. The flaring end 4 may then be tightly held between the teeth or between the lips. Any type of cigarette may be employed, that is, the usual type of cigarette or a cigarette having a cork tip. The outwardly flared end 4 may serve as a support for the cigarette as illustrated in Fig. 5 enabling the cigarette to stand vertically on a supporting table top such as illustrated at 6 in Fig. 5. The lighted cigarette may, in this way, be supported intermediate the smoking intervals.

Fig. 6 shows a modified form of cigarette tip constructed according to my invention and in which a ring member 7 is secured directly to the tip 2 to enable the tip to be held by a finger as represented in Fig. 8.

The Venturi shaped tip may have the outside area thereof provided with ornamentation or advertising, the surface of the tip being such that a minimum amount of cosmetic is removed from the lips and maximum protection is afforded to the smoker.

While I have described my invention in one of its preferred embodiments, I desire that it be understood that modifications may be made and that no limitations upon my invention are intended other than are imposed by the scope of the appended claim.

What I claim as new and desire to secure by Letters Patent of the United States is as follows:

110

A tip for cigarettes comprising a Venturi-shaped tubular member having a portion of minimum cross-section midway its length for snugly confining the end of a cigarette, said tubular member gradually increasing in diameter towards both ends to form flared front and rear end portions whereby a cigarette may be thrust into the tubular member through the front end thereof and wedged into its intermediate portion with the inserted end of the cigarette terminating in spaced relation to the rear end of the tubular

member, and a finger engaging ring disposed beneath the front end portion of the tubular member, said ring being disposed at right angles to the tubular member and having its upper portion firmly united to the tubular member at the front end thereof, said ring being spaced from the rear end of the tubular member and serving as an abutment to engage a person's lower lip when the rear end portion of the tubular member is placed in a person's mouth during smoking.

HELEN HILL.
